US0D1030637S

(12) **United States Design Patent** (10) **Patent No.:** **US D1,030,637 S**
(45) **Date of Patent:** **** Jun. 11, 2024**

(54) **PORTABLE POWER SUPPLY**

(71) Applicant: **Dansheng Zhao**, Shenzhen (CN)

(72) Inventor: **Dansheng Zhao**, Shenzhen (CN)

(**) Term: **15 Years**

(21) Appl. No.: **29/861,787**

(22) Filed: **Dec. 2, 2022**

(51) **LOC (14) Cl.** **13-02**

(52) **U.S. Cl.**

USPC **D13/103**

(58) **Field of Classification Search**

USPC D13/103-106, 110, 118, 119, 184, 199;
D14/253, 432, 434

CPC H01M 6/00; H01M 6/14; H01M 6/10;
H01M 10/52

(57) **CLAIM**

The ornamental design for a portable power supply, as shown and described.

DESCRIPTION

FIG. 1 is a front, left and bottom perspective view of a portable power supply, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the portable power supply that form no part of the claimed design.

1 Claim, 7 Drawing Sheets
